UNITED STATES PATENT OFFICE

1,976,809

BUS OR CAR WINDOW CONSTRUCTION

Joseph Schunk, Newark, N. J., assignor to National Lock Washer Company, Newark, N. J., a corporation of New Jersey

Application August 24, 1933, Serial No. 686,534

4 Claims. (Cl. 189—73)

The present invention relates to bus or car window construction, and more particularly to improved means for holding the stops of a window sash casing in place on the post piece of the window frame, such stops being either inside or outside type, an object of the invention being to provide a construction which will reliably hold the stops in their proper positions in the frame, and will permit them to be easily and quickly fastened and unfastened.

With the above and other objects in view, embodiments of the invention are shown in the accompanying drawing, and these embodiments will be hereinafter more fully described with reference thereto, and the invention will be finally pointed out in the claims.

As the construction, according to the invention, is the same on each side of the window opening, only one side or post of said opening will be shown in the illustrated adaptation of the invention.

In the drawing:

Fig. 1 is a fragmentary outside elevation.

Fig. 2 is a vertical sectional view, taken along the line 2—2 of Fig. 1, and showing the holding means for a removable inside stop of a window casing.

Fig. 3 is a horizontal sectional view, taken along the line 3—3 of Fig. 2.

Fig. 4 is a horizontal sectional view, taken along the line 4—4 of Fig. 3.

Fig. 5 is a horizontal sectional view, taken along the line 5—5 of Fig. 3.

Fig. 6 is a longitudinal sectional view, similar to Fig. 3, and showing a modified form of the invention in which the holding means is provided in relation to a removable outside stop of a window casing, and

Fig. 7 is a vertical sectional view, taken along the line 7—7 of Fig. 6.

Similar numerals of reference will be used to denote like parts in the several figures of the drawing.

Referring to Figs. 1 to 5 of the drawing, 1 represents the window casing, and 2 generally denotes the outside stop which is made of metal. This outside stop comprises a comparatively wide member 3 which has a leg 4 abutting the post, a member 5 that extends inwardly and is spaced from the post and is then stepped flush with the leg 4 and abuts the post, as shown at 6, and immediately beyond the riser 7 of the stepped portion is a comparatively narrow member 8 which is integral with the stop 2 and parallel to the member 3, the spacing between the riser 7 and

member 8 forming a groove 9. The portion 6 extends beyond the member 8 and terminates in a lip 10 that is parallel to said member.

The stop is secured to the post, at suitable intervals by screws 11, (only one of which is shown) the space between the member 5 and the post preferably containing any suitable packing 12, such as felt, so as to prevent dirt or moisture from entering.

The window sash glass 13 has its side edges bound in glazing tape 14 and contained in a channel side strap 15 adapted to slide within felt channels 16, these channels 16 being backed by a metal retaining strip which has a portion 17 that extends behind the channel, and an outer portion 18 that extends along the outer face of the channel and abuts snugly against the inner surface of the member 3, said portion 18 terminating in a lip 19 that overlaps the outer leg of the channel and serves to keep the latter in place. Springs 20 secured by the screws 11 to the member 5 yieldingly back up the metal strip and channel.

The inside stop 21 is of generally H-shape, and is inserted by rolling one leg over the slightly protruded end 22 of the member 8 into the channel 9 and in abutting relation to the inner leg of the felt channel 16, the outer leg seating upon the member 6 adjacent the lip 10. A lip 23 on the stop overlaps the end of the inner leg of the felt channel 16 and co-operates with the lip 19 in holding the channel in place.

When the inside stop is thus placed in position, it will be noted that the pressure of the felt channel is outwardly upon the outer end of the stop 21, pressing the inner end of the inner leg against the inner wall 7 of the groove 9 about the protrusion 22 on the end of the member 8 as a fulcrum, the stop being thus held in position and in turn retaining the felt channel 16.

In order to fasten the inside stop in position the inner leg of the stop is provided at suitable intervals along its edge disposed in the groove 9 with notches 24 having inclined slots 25 extending therefrom in a generally longitudinal direction and which are adapted to be engaged by projecting pins 26 secured to the member 8, the engagement being effected by first engaging the pins in the notches 24 and thereupon moving the stop longitudinally, whereupon the pins enter the slots 25 with a wedging action to secure the stop in place. The stops are thereupon locked in position, and for this purpose the member 8 is provided with a transversely bent lug 27 disposed in the plane of a screw 28 provided in an enlargement 29 of the

cross part of the stop. With this screw withdrawn a sufficient distance to clear the lug 27 the stop may be freely moved in a longitudinal direction either to engage or disengage it. When 5 fully engaged the screw 28 is screwed in as shown in Figs. 3, 4 and 5 into obstructing position behind one end of the lug 27 thus preventing retractive movement on the stop.

In Figs. 6 and 7 I have shown a modification in 10 which the outside stop is removable, and is adapted to be positioned and locked in a substantially similar manner to the first embodiment. In this case the outside stop has a comparatively narrow member 30 having an inwardly directed protrusion 31 at its end, while the member 5 is spaced from the post as described, but is also spaced from the member 30 so as to form a groove 32, the inside stop 21 being integral with the parts of the outside stop just described, and the felt 15 channel retainer 16—17 being reversed as compared with the retainer of the first embodiment, the lip 19 overlapping the inner leg of the channel.

In this modified construction the same method of positioning the sash is employed, since in this 20 instance, the sash is put in position from the outside of the vehicle instead of the inside, it being merely necessary to pull the outer leg of the felt channel 16 outwardly, locate the sash therein, and then roll a separate comparatively wide outside 25 stop member 33 over the member 30 and force it into the groove 32, this member 33 having a lip 34 which overlaps the adjacent leg of the channel and co-operates with the lip 19 to hold the felt channel in place. When the member 33 30 is in position it is firmly held by the groove 32, the outward thrust of the outer leg of the felt channel and the member 30.

In order to fasten the stop in position it is provided, in a substantially similar manner to the 35 first embodiment, along its edge disposed in the groove 32 with notches 34, having inclined slots 35 extending therefrom and which are engaged by pins 36 secured to the member 32. For the 40 purpose of locking the stop in position a stop block 37 is slidably mounted in a transverse slot 38 formed in the base of the groove 32 and extending inwardly in the member 5, a screw 39 rotatable in an aperture in the member 32 being threaded into the block and adapted upon being 45 turned to impart transverse movement to it. Within the member 33 there is provided a rectangular notch 40 adapted to receive the block 37 in the locking position and a longitudinal notch 41 extending from one side of the notch 34 and 50 55 which clears the screw in the unlocked position and during longitudinal movement of the stop 33. It will be obvious that in the unlocked position the screw 39 is turned to move the block 37 inwardly out of blocking relation from the notch 40, and in the locked relation the screw is turned 60 in the opposite direction drawing the block tightly against the inner surface of the member 30 and in blocking relation in the notch 40.

I have illustrated and described a preferred and 65 satisfactory embodiment of the invention but it will be obvious that changes may be made therein, within the spirit and scope thereof, as defined in the appended claims.

Having thus described my invention, what I 70 claim and desire to secure by Letters Patent is:—

1. In a window construction, a window post, a glass sash having its edge in relation to said post, a stop fixed to said post and disposed at one side of said sash to retain it, a removable 75 stop member disposed at the other side of said

sash and abuttingly engaged at one edge against said fixed stop in the assembled relation, said removable stop member adapted to be moved longitudinally of said post, inclined bayonet slot and pin means cooperating between said post and said removable stop member adapted to interlockingly engage with a wedging action upon movement of said removable stop member in one direction and to disengage upon movement in the other direction, the edge of said removable stop member being out of frictional contact with said fixed stop during said longitudinal movement. 80 85

2. In a window construction, a window post, a glass sash having its edge in relation to said post, a stop fixed to said post and disposed at one side of said sash to retain it, a removable stop member disposed at the other side of said sash and abuttingly engaged against said fixed stop in the assembled relation, said removable stop member adapted to be moved longitudinally of said post, 90 said removable stop member having inclined bayonet slots in its edge, and pins fixed to said post adapted to interlockingly engage said slots with a wedging action upon movement of said removable stop member in one direction and to dis- 95 engage upon movement in the other direction, the edge of said removable stop member being out of frictional contact with said fixed stop during said longitudinal movement. 100

3. In a window construction, a window post member, a glass sash having its edge in relation to said post, a stop fixed to said post and disposed at one side of said sash to retain it, a removable stop member disposed at the other side of said sash and abuttingly engaged against said 110 fixed stop in the assembled relation, said removable stop member adapted to be moved longitudinally of said post member, inclined bayonet slot and pin means cooperating between said post member and said removable stop member adapt- 115 ed to interlockingly engage with a wedging action upon movement of said removable stop member in one direction and to disengage upon move- 120 ment in the other direction, the edge of said removable stop member being out of frictional con- 125 tact with said fixed stop during said longitudinal movement, and adjustable means on one of said members adapted to be disposed in relation to the other member to prevent longitudinal move- 130 ment of said removable stop member in disengag- 135 ing direction.

4. In a window construction, a window post, a glass sash having its edge in relation to said post, a stop fixed to said post and disposed at one side of said sash to retain it, a removable stop member disposed at the other side of said sash and abuttingly engaged at its edge against said fixed stop in the assembled relation, said removable stop member adapted to be moved longitudinally of said post, inclined bayonet slot and pin means 140 cooperating between said post and said removable stop member, said bayonet slot means including a recess portion extending parallel to said post and removable stop member and open at one edge to permit transverse engagement and disengagement of said pin means and an inclined slot portion extending therefrom and adapted to interlockingly engage with a wedging action upon move- 145 ment of said stop member in one direction and to disengage upon movement in the other direction, the edges of said removable stop member being out of frictional contact with said fixed stop dur- 150 ing said longitudinal movement.

JOSEPH SCHUNK.
